Primary Examiner — Karen E Eldridge Powers(74) *Attorney, Agent, or Firm* — Knobbe, Martens, Olson & Bear, LLP(57) **CLAIM**

The ornamental design for a charging dock, as shown and described.

DESCRIPTION

FIG. 1 is a top, front and right-side perspective view of a charging dock;

FIG. 2 is a bottom, rear and right-side perspective view of the charging dock;

FIG. 3 is a front view of the charging dock;

FIG. 4 is a rear view of the charging dock;

FIG. 5 is a right-side view of the charging dock;

FIG. 6 is a left-side view of the charging dock;

FIG. 7 is a top view of the charging dock; and,

FIG. 8 is a bottom view of the charging dock.

The broken lines shown in the drawings represent portions of the charging dock that form no part of the claimed design. The illustrated embodiment is shown with a symbolic break in its length. The broken-away symbols in the drawings indicate that any portion of the article beyond what is shown forms no part of the claimed design.
